(57) **CLAIM**

We claim the ornamental design for a pull-out cabinet tower, as shown and described.

DESCRIPTION

FIG. 1 is a top perspective view of a pull-out cabinet tower.

FIG. 2 is a right side elevation view thereof.

FIG. 3 is a left side elevation view thereof.

FIG. 4 is a front elevation view thereof.

FIG. 5 is a rear elevation view thereof.

FIG. 6 is a top plan view thereof; and,

FIG. 7 is a bottom plan thereof.

The broken lines in FIGS. 1-7 are for the purpose of illustrating environmental structure and form no part of the claimed design.
